SELF-FORMING POURING SPOUT FOR CONTAINERS

Frank D. Bergstein, Cincinnati, Ohio, assignor to Bergstein Packaging Trust, a trust composed of Robert Bergstein and Frank D. Bergstein, trustees

Application February 21, 1957, Serial No. 641,750

12 Claims. (Cl. 222—531)

This invention relates to pouring spouts for containers or cartons and more particularly to the provision of a pouring spout in the nature of a foil patch associated with the interior surface of the carton or its liner in registry with a displaceable flap formed in a wall of the carton, the arrangement being such that outward displacement of the flap will result in the automatic formation of the foil patch into a pouring spout projecting from the opening defined by the displaced flap.

The use of conventional pre-formed metallic spouts has presented certain problems where the material to be dispensed is of such character that it requires protection from the outside atmosphere. Since the application of the conventional pouring spout requires the cutting of slots in the carton for the passage of the wings or sides of the spout as well as additional perforations for the hooks or prongs used to secure the spout in place, an overwrap of an impervious material must be provided if proofness is to be obtained. Such overwrap not only adds materially to the cost of the package and requires separate handling operations, but in addition the user must first sever or otherwise remove a portion of the wrapper to gain access to the pouring spout. The same considerations are true where the container itself is of proofed character, i. e. wax or polyethylene coated board, and only the spout and surrounding area is covered by a protective patch. The alternative to externally proofing the carton is the provision of an inner liner which may be fabricated as an integral part of the carton as, for example, in accordance with the teachings of Bergstein Patents 2,099,257 and 2,250,249. However, where a conventional pre-formed pouring spout is used in conjunction with an inner liner, the wings of the spout puncture the liner and hence cause considerable damage to the protective qualities of the liner. Even the use of a protective covering over the spout does not obviate this difficulty since moisture vapor will penetrate the board beyond the patch and strike through to the lines of puncture.

In accordance with the instant invention, I provide a spout-forming foil patch which is initially applied to the inner surface of the liner in alignment with a deflectable flap in the carton body, the central or base portion of the foil patch being secured to the liner which is in turn secured to the flap so that outward movement of the flap will cause the liner to be broken away along lines coinciding with the side edges of the opening defined by the displaced flap. The outward movement of the base portion of the spout causes the side portions or wings to be folded at right angles as they are withdrawn through the opening, thereby automatically folding the spout parts to erected condition. Alternatively, the spout may be pre-formed, i. e. the wing portions folded relative to the base portion prior to attachment to the liner. Of course, where no liner is employed, the spout forming patch may be secured directly to the inner surface of the flap.

A principal object of my invention is the provision of

2

a pouring spout of the character described which will be self-forming upon outward displacement of the flap to which it is secured.

A further object of my invention is the provision of a pouring spout formed from a patch of aluminum foil, the patches preferably being formed from a roll of foil as an incident of a continuous operation.

A further object of my invention is the provision of a proofed carton or container in which the liner is retained in imperforate condition until such time as it is desired to use the pouring spout, whereupon the liner may be ruptured and the pouring spout formed in a single manipulative step.

Still a further object of my invention is the provision of a pouring spout structure which is extremely easy to fabricate as an incident of the fabrication of the carton itself and which effects economies and advantages hitherto unobtainable in a container incorporating an integral pouring spout.

20 The foregoing, together with other objects of my invention which will appear hereinafter or which will be apparent to the skilled worker in the art upon reading these specifications, I accomplish by those constructions and arrangements of parts of which I shall now describe certain exemplary embodiments.

Reference is now made to the accompanying drawings wherein:

Figure 1 is a fragmentary perspective view of a carton blank formed in accordance with my invention.

30 Figure 2 is a fragmentary plan view illustrating the formation of a pouring spout patch from a roll of aluminum foil.

Figure 3 is a fragmentary plan view illustrating the manner in which the foil patch of Figure 2 is secured to the carton blank.

Figure 4 is a perspective view of an erected carton incorporating the pouring spout.

Figure 5 is a vertical sectional view taken along the line 5—5 of Figure 4.

Figure 6 is a horizontal sectional view taken along the line 6—6 of Figure 4.

Figure 7 is a fragmentary perspective view illustrating the pouring spout in pouring condition.

45 Figure 8 is a horizontal sectional view similar to Figure 6 but illustrating the pouring spout in pouring condition.

Figure 9 is a fragmentary plan view similar to Figure 3 but illustrating an alternative form of construction.

Figure 10 is a fragmentary perspective view illustrating 50 the spout of Figure 9 in pouring condition.

Figure 11 is a plan view of a device suitable for applying the foil patches to the erected and open-ended containers.

55 Figure 12 is an elevational view with parts in section of the device of Figure 11.

Figure 13 is a fragmentary vertical sectional view illustrating the carton of Figure 12 with the spout forming patch positioned therein.

Figure 14 is a vertical sectional view taken along the line 14—14 of Figure 12.

Figure 15 is a vertical sectional view taken along the line 15—15 of Figure 13.

Figure 16 is a fragmentary plan view of yet another embodiment of my invention.

Figure 17 is a fragmentary perspective view of a carton and liner incorporating the embodiment of Figure 16.

70 Figures 18 and 19 are vertical sectional views taken along the line 18—18 of Figure 17 and illustrate alternative positions of the pouring spout.

From the outset it will be understood that the form of carton or container employed does not constitute a

limitation on my invention and it may be of either the knock-down or set-up variety. Preferably, where an inner liner is to be used, the carton will be of the knock-down variety in which the liner is associated with the carton blank, whereupon the carton body walls are tubed about the liner and adhesively secured thereto.

Referring now to Figure 4 of the drawings, I have therein illustrated a conventional tuck-end carton having body walls 1, 2, 3 and 4 in articulation and joined together by means of a glue flap 5. Suitable end closure flaps, such as the flaps 6, 7 and 8, are provided at the ends of the body walls, as will be readily understood by the worker in the art. In accordance with my invention and as best seen in Figure 1, a deflectable flap 9 is formed near the upper end of one of the body walls, such as the body wall 3, the deflectable flap being hingedly connected to the wall at its lower end along the score line 10. In order that the user may readily engage the upper free edge of the flap 9, I prefer to provide a supplementary flap 11 oppositely directed with respect to the flap 9 and hingedly connected to the carton body wall along the score line 12. With this arrangement, the user may readily deflect the supplementary flap 11 inwardly with the tip of his index finger, thereby enabling him to engage the free upper edge of the flap 9 and move it outwardly. Where the carton is lined, a knife blade may be first inserted between the edges of the two flaps to sever the liner. Once severed in this manner, the liner will readily tear along the side edges of the flap as it is moved outwardly and the wings drawn through the opening so formed.

Figure 2 illustrates a foil patch 13 from which the pouring spout is formed. Preferably, the patch will be formed from dead-soft aluminum foil having a thickness of .005", although it is to be understood that this exemplary embodiment does not constitute a limitation on my invention. The foil patch comprises a body or base portion 14 centrally disposed with respect to a pair of side or wing portions 15 and 16 separated in part from the base portion by lines of cut 17 and 18 projecting inwardly from the lower edge of the patch. As illustrated in dotted lines in Figure 2, the patches may be formed in nested relation from a strip or roll of foil 19, thereby greatly facilitating their formation.

Figure 3 illustrates the attachment of the foil patch 13 to the wall 3 of the carton body. As shown therein, the dimensions of the foil patch are such that the lines of cut 17 and 18 lie in prolongation of the side edges of flap 9 with their upper edges coinciding with the ends of score line 10. The depth of the patch is such that its upper edge substantially coincides with the upper free edge of flap 9. The body or base of the patch thus in part overlies the flap 9 and, as to the portion thereof between the lines of cut 17 and 18, overlies the portion of body wall 3 immediately beneath score line 10. The base is adhesively secured to the underlying parts by means of the adhesive area 20 which may be applied either to the patch or to the carton. In a preferred form of the invention, the foil patch is itself surface coated with a heat sealable material, such as polyethylene, which permits the patch to be heat sealed directly to the carton or liner, as the case may be, thereby eliminating the necessity of interposing a liquified bonding adhesive. While the liner has been omitted from the embodiment illustrated, it will be obvious that the liner may be interposed between the body wall 3 and the foil patch, in which event the liner itself will be secured to at least the flap 9.

It will be evident from the foregoing that the spout forming patch may be applied in flat condition to the inner surface of the box where it will be completely out of the way and will not interfere with subsequent filling operations. It has been found that exact registry between the patch and the flap is not essential to the successful operation of the spout and consequently some variation

5 may be tolerated without destroying the effectiveness of the spout. To open the spout, the user has simply to deflect the supplementary flap inwardly with his finger, as illustrated in Figure 5, thereby engaging the upper edge of flap 9, whereupon outward movement of the flap 9 will result in bringing the pouring spout to the condition illustrated in Figure 7. As the base of the spout is moved outwardly, it will be evident that the wing portions 15 and 16 will be swept rearwardly by the side edges of the opening, thereby bringing them to a position at substantially right angles to the base. This sweeping action is diagrammatically illustrated by the dotted lines in Figure 8. The action is automatic and the inherent dead-folding characteristic of the aluminum foil causes the wings to remain in the folded position. The wings also bear against the sides of the opening and hold the spout in open position. The spout may be readily retracted when it is desired to reclose the pouring opening. Upon reclosure it will be noted that the flap 9 returns to its original position with its side edges in edge abutting relation to the side edges of the opening and the spout lies wholly within the confines of the carton body.

20 In Figures 9 and 10, I have illustrated a modified form of pouring spout wherein the supplementary flap 11 is omitted. Short notches or lines of cut 21 and 22 are provided in upward prolongation of the side edges of the opening defined by the flap 9, and the uppermost edges of the wings 15 and 16 are projected upwardly to provide humps or extensions 23 and 24. When the spout is formed upon opening of the flap 9, as seen in Figure 10, the automatic folding of the wings 15 and 16 causes the extending upper edges 23 and 24 to enter the slots or notches 21 and 22, respectively, the slots thus serving as guides for the free edges of the wings. This is particularly desirable where relatively light weight foil is employed and averts the possibility of the wings being folded inwardly to the extent that they will be spaced from the side edges of the opening. Initially, this form of spout may be readily opened by inserting a knife blade along the upper edge of the flap 9 and moving the flap outwardly.

25 In Figures 11 and 12, I have illustrated an exemplary device for applying the foil patches to a set-up carton. The device is intended for the small user who will receive the cartons in knock-down form, set them up, apply the foil patch and then transfer the cartons to a filling device. Alternatively, the foil patches may be applied as an incident of the manufacture of the cartons or, for large users, the patches may be applied as an incident to a continuous filling operation wherein the erected cartons are placed in cages or the like for continuous delivery to the filling instrumentality. In such case, the continuous feeding device may be provided with a patch applying station to which the cartons will be delivered prior to their delivery to the filling instrumentality.

30 In the device illustrated, the carton is placed in a jig 30 with the wall containing the flap 9 lowermost and the open upper end of the carton projecting outwardly beyond the jig. A mandrel 31 is positioned immediately beyond the open end of the carton, and mandrel being connected at one end to a shaft 32 journaled in brackets 33. The arrangement is such that movement of lever arm 34 will cause the mandrel to move in an arcuate path, as indicated in Figure 12, from a patch receiving position A to a patch applying position B. Thus, a patch 13 may be removed from the supply 35 and positioned on the free end of the mandrel, preferably with the wings bent downwardly, whereupon the mandrel will be swung from position A to position B, thereby juxtaposing the patch to the flap 9. A liquid adhesive may be applied to the base portion of the patch as it is positioned on the mandrel, or, where the patch has a heat reactive coated surface of heat sealable material, the mandrel may be heated, as by a heating element 36 which will cause the patch to be heat sealed in place within the car-

ton. As will be evident, the patch may be sealed directly to the inner surface of the carton body wall, or it may be sealed to the inner surface of a liner, such as the liner 37.

As seen in Figure 14, it is also in the spirit of my invention to pre-form or pre-fold the wings 15 and 16 prior to the attachment of the foil patch to the carton. This may be readily done simply by folding the wings downwardly about the mandrel or form 31 in the manner illustrated. Where this is done, the removal of the mandrel following application of the patch to the carton will result in the outfolding of the wings, as seen in Figure 15, from the position illustrated in dotted lines to the position illustrated in solid lines in which the wings lie at substantially right angles to the base portion 14. The spout still lies wholly within the confines of the carton body, although in this instance the wings will project inwardly into the carton as will be evident from Figure 13.

Figures 16 through 19 illustrate a slightly modified form of my invention wherein an arcuate opening 38 is provided immediately above the flap 9 so as to expose a small portion of the liner 37. With this arrangement, the user may readily insert a knife or other sharp object, such as is diagrammatically illustrated at 39 in Figure 18, to sever the liner along the upper edge of the flap 9, whereupon the upper edge of the flap may be readily engaged and moved outwardly to effect the formation of the pouring spout.

From the foregoing, it will be apparent that my invention contemplates a metallic spout which, in contrast to the conventional spout, lies on the inside of the carton with its base secured to the inner surface of the carton wall and its wings either extending along the wall or projecting into the interior of the carton body. The wings do not puncture the carton wall, or liner, until the user has opened the flap and caused the spout to be automatically formed into operative position. In fact, with the instant spout structure, all precuts in the carton could be eliminated entirely and the user could form the flap by cutting along lines defining three sides of the flap.

Modifications may, of course, be made in my invention without departing from the spirit of it and consequently I do not intend the invention to be limited excepting in the manner set forth in the claims which follow. Having thus described my invention in certain exemplary embodiments, what I claim and desire to secure by Letters Patent is:

1. In a dispensing container having a wall, a pouring opening defined in said wall by a flap which, when displaced from the plane of said wall, has free upper and side edges with its lower edge hingedly connected to said wall along a line of fold, and a pouring spout juxtaposed to the inner surface of said wall in the area of said flap, said pouring spout being formed from metal foil having dead-folding characteristics and configured to define a centrally disposed base portion of a width substantially equal to the width of said flap and foldable wing portions projecting outwardly from the opposite sides of said base portion, said base portion having an integral extension projecting downwardly beyond the lower edge of said flap and bridging the line of fold connecting said flap to said wall, the said base portion and its extension having a coating of heat sealable material thereon by means of which said base portion is secured to said flap and said extension is secured to said wall in the area immediately beneath said flap, whereby upon the outward placement of said flap the base portion of said pouring spout will be folded along a line coinciding with the fold line of said flap and the dead-folding characteristics of said metal foil will serve to maintain the spout in its outwardly displaced position, the outward displacement of the flap serving to draw the wing portions of said spout through the pouring opening with their outer surfaces in contact with the opposite side edges of the said opening.

2. A self-forming pouring spout construction comprising, in combination, a carton having enclosing body walls,

a pouring opening formed in a wall of said carton, said opening being normally closed by a flap hingedly connected to the said wall along an edge of said opening, an inner liner in said carton body, said liner being secured to the inner surface of said flap, and a pouring spout secured to the inner surface of said liner in the area of said flap, whereby said spout is effectively secured to said flap, said spout comprising an intermediate base portion having a width substantially equal to the width of said flap, and wing portions projecting outwardly from the opposite sides of said base, said pouring spout initially lying wholly within the confines of said inner liner whereby upon outward deflection of said flap and the severance of said liner about three contiguous edges of said flap, said base portion of said spout will be drawn through said pouring opening with said wing portions folded inwardly as they are drawn along the edges of the opening adjacent said first named edge to which said flap is hingedly connected.

3. The self-forming pouring spout construction claimed in claim 2 wherein said pouring spout has a surface thereof coated with a heat-sealable material, and wherein the base portion of said pouring spout is secured to said liner by means of said heat-sealable coating.

4. The structure claimed in claim 3 wherein said liner has a heat-sealable coating on its outer surface, and wherein in said liner is secured to said flap by means of said heat-sealable coating.

5. In a pouring spout construction, a carton having a pouring opening defined by a flap struck from a wall of said carton, a proofing liner within said carton, said liner being secured to said flap, and a flexible pouring spout structure adapted to be projected through said pouring opening upon outward displacement of said flap, said pouring spout structure comprising a base part secured to the inner surface of said liner in the area of said flap, said base part having a width substantially equal to the width of said flap, and wing parts projecting outwardly beyond opposite side edges of said base.

6. The construction claimed in claim 5 wherein said wing parts are initially angularly disposed with respect to said base part.

7. The structure claimed in claim 5 wherein said pouring spout is initially planar, and wherein said wing parts are folded relative to said base part as said flap is deflected outwardly and said liner severed about the edges of said pouring opening.

8. In a pouring spout construction, a carton having a pouring opening defined by a flap adapted to be struck from a wall of said carton, a liner within said carton, said liner being secured to the inner surface of said flap, and a pouring spout structure having a base and wing parts, the base of said pouring spout being secured to the inner surface of said liner in registry with said flap, whereby upon the rupture of said liner and the outward deflection of said flap, said pouring spout will be moved through said pouring opening to operative position.

9. The pouring spout construction claimed in claim 8 including a supplementary flap struck from the said wall of the carton with its free end edge coinciding with the free end edge of said first named flap, said supplementary flap being deflectable inwardly to expose the free end edge of said first named flap.

10. A method of providing a pouring spout for a carton structure which comprises providing a flat-folded carton body having a pouring opening defined in a wall thereof and normally closed by a flap hingedly connected to said wall along an edge of said opening, erecting said carton body and depositing within said body a foil patch having a base part and wing parts projecting from opposite sides of said base part, said patch being positioned with its base part in registry with the flap in said wall, the base part at least of said foil patch having a heat sealable coating thereon, including the step of securing the base part only of said patch to said flap by the application of heat and pressure thereto.

11. The method claimed in claim 10 wherein said base has a portion thereof extending beyond the hinged connection of said flap to said wall, and wherein said extending portion of said base has a heat sealable coating thereon and is secured to the underlying portion of said wall by the application of heat and pressure to the extending portion of said base, whereby to impart the dead-folding characteristics of said foil patch to said flap.

12. A method of providing a pouring spout for a lined carton structure which comprises providing a tubular carton body having an inner liner the outer surface of which is heat sealable and a pouring opening defined in a wall thereof and normally closed by a flap hingedly connected to said wall along an edge of said opening, depositing within said inner liner a foil patch having a base part

10

5

15

coated with a heat sealable material and wing parts projecting from opposite sides of said base part, said patch being positioned with its base part in registry with the flap in said wall, including the step of concurrently securing said liner to said flap and securing the base of said patch to said liner in the area of said flap by the application of heat and pressure to the base part of said patch.
